UNITED STATES PATENT OFFICE.

THOMAS WRIGHT, OF JERSEY CITY, NEW JERSEY.

DUMP-WAGON.

1,086,833.

Specification of Letters Patent. Patented Feb. 10, 1914.

Application filed February 20, 1913. Serial No. 749,710.

To all whom it may concern:

Be it known that I, THOMAS WRIGHT, a citizen of the United States, residing at Jersey City, in the county of Hudson and State of New Jersey, have invented a new and useful Dump-Wagon, of which the following is a specification.

This invention relates to dump wagons and more particularly to motor driven wagons of this character, the principal object of the invention being to provide means whereby the motor used for propelling the vehicle can also be used for elevating the body relative to the chassis of the machine.

Another object is to provide a vehicle of this character in which the body can be elevated either by means of the motor or by hand power.

A further object is to provide improved mechanism for transmitting motion to the lifting elements from the drive shaft of the vehicle.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a side elevation of a vehicle having the present improvements combined therewith. Fig. 2 is a plan view of the mechanism constituting the present invention. Fig. 3 is a side elevation of said mechanism.

Referring to the figures by characters of reference 1 designates the chassis of a motor vehicle, said chassis normally supporting a body 2. This body may be provided with elevating arms 3 connected to the body by links 4, the lower ends of the arms being mounted to travel along inclined rails 5. The means for lifting the body off of the chassis does not constitute any part of the present invention and the structure shown for this purpose has already been set forth in Patent No. 1,019,211 issued to me on March 5, 1912, although it is to be understood that any other desired mechanism

may be employed if desired. A winding drum 6 is mounted for rotation upon the chassis and has chains, cables or other flexible elements 7 secured thereto and adapted to be wound thereon, these flexible elements being attached to the lower ends of the arms 3 so that, when the said elements are wound upon the drum, the lower ends of the arms 3 will be drawn toward each other and said arms will thus operate to lift the body 2 off of the chassis 1.

The longitudinal drive shaft of the motor vehicle has been indicated at 8 and serves to transmit motion from the motor, not shown, to the propelling wheels of the vehicle. This shaft is the one usually provided. In order to utilize the propelling motor for the purpose of elevating the body 2 of the wagon, it is necessary to secure a gear 9 to the shaft 8. This gear meshes with a larger gear 10 secured to a sleeve 11 mounted for rotation within a bearing 12, there being a clutch member 13 secured to and revolvable with the sleeve. A shaft 14 is journaled in the sleeve and has a sprocket 15 secured to it, there being a clutch member 16 feathered on the shaft and adapted to be shifted into and out of engagement with the clutch member 13 by means of a lever 17 which can be readily reached from one side of the vehicle. Sprocket 15 is adapted to transmit motion, through a chain 18, to a sprocket 19 secured to a counter shaft 20, there being a small gear 21 feathered on the shaft 20 and adapted to be shifted longitudinally thereon by means of a lever 22. Gear 21 is adapted to mesh with a large gear 23 secured to the shaft 24 on which drum 6 is secured and another small gear 25 meshes with gear 23 and has a central angular stud or projection 26 whereby the said gear can be rotated readily by placing a crank in engagement with the stud.

It is of course to be understood that under normal conditions, the clutch members 13 and 16 are out of engagement with each other and, therefore, the shaft 8 although rotating, will not actuate the winding mechanism. Only the gears 9 and 10 and the clutch member 13 will rotate during the actuation of shaft 8. Should it be desired to elevate the body 2 by hand, as ordinarily, lever 22 is shifted so as to disengage gear 21 from gear 23. A crank or other suitable device is then placed in engagement

- 2
- with stud 26 and the small gear 25 is rotated so that motion will thus be transmitted to the large gear 23, and thence through shaft 24 to the winding drum 6.
- 5 Should it be desired to elevate the body 2 by utilizing the power of the motor on the vehicle, the shaft 6 is kept rotating while the machine is standing still and, after shifting gear 21 into mesh with gear 23, lever 17 is shifted so as to bring the clutch member 16 into engagement with the rotating clutch member 13. Motion will therefore be transmitted from shaft 8 through gears 9 and 10, clutch members 13 and 16 and sprocket 15 to chain 18 and this chain will drive sprocket 19, shaft 20 and gear 21 which, in turn, will actuate gear 23, shaft 24 and drum 6. As soon as the body has been raised to the desired elevation, the 20 clutch member 16 is shifted out of engagement with clutch member 13.

Any suitable mechanism can of course be provided for holding the body raised after it has been elevated by means of the 25 mechanism described. Such means, however, does not constitute any part of the present invention.

When the holding means is disengaged from the elevating mechanism, the body of 30 the wagon will gravitate to its initial position, this movement causing the operation of the mechanism to reverse and the cables 7 to unwind from the drum 6.

What is claimed is:—

- 35 1. The combination with a motor propelled vehicle including a longitudinally disposed drive shaft, a vertically movable body, and lifting devices for the body, of a gear, means upon the same shaft there-
40 with and actuated thereby for operating the lifting devices, a hand actuated gear con-stantly meshing with the first named gear.

another gear shiftable into and out of mesh with the first mentioned gear, a transverse shaft, a clutch member feathered thereon, means revoluble with said transverse shaft for transmitting motion to said shiftable gear to rotate it, a driving clutch member, means for transmitting motion thereto from the drive shaft, and means for shifting one 50 of the clutch members into and out of engagement with the other clutch member.

2. The combination with a motor propelled vehicle including a vertically movable body and lifting means coöperating with the body, of a longitudinal drive shaft for actuating the vehicle, a transverse winding element interposed between said lifting means, oppositely extending flexible means connected to the winding element for actuating the lifting means, a gear revoluble with the winding element, said gear and element being mounted upon the same shaft, a hand actuated gear constantly meshing with said first mentioned gear, a counter shaft, a 65 gear feathered thereon, means for shifting said gear into and out of mesh with the first named gear, a revoluble sleeve, a gear thereon, a gear upon the drive shaft constantly meshing with the gear upon the 70 sleeve, a transverse shaft journaled within the sleeve, a clutch member carried by the sleeve, a clutch member feathered upon the transverse shaft, means for actuating said feathered clutch member, and means for 75 transmitting motion from the transverse shaft to the counter shaft.

In testimony that I claim the foregoing as my own, I have hereto affixed my signature in the presence of two witnesses.

THOMAS WRIGHT.
